UNITED STATES PATENT OFFICE.

WILLIAM CROSSER, OF EVERGREEN, COLORADO, ASSIGNOR OF ONE-THIRD TO RUDOLPH WISMEYER, OF BROOKVALE, COLORADO.

RAILROAD-TIE.

1,184,627.

Specification of Letters Patent. Patented May 23, 1916.

Application filed October 25, 1915. Serial No. 57,811.

To all whom it may concern:

Be it known that I, WILLIAM CROSSER, a citizen of the United States, residing at Evergreen, in the county of Jefferson and State of Colorado, have invented new and useful Improvements in Railroad-Ties, of which the following is a specification.

The present invention relates to improvements in the construction of ties for railroad 10 rails.

In carrying out my invention it is my purpose to provide a reinforced plastic tie having a yieldable rail seat so that the resiliency of the ties will not be impaired when 15 the rolling stock passes over the portions of the rails supported upon the ties.

A still further object of the invention is to construct a tie wherein the employment of wood or similar perishable material will 20 be entirely dispensed with.

A still further object of the invention is to produce a tie for railway rails which shall embody the desirable features of simplicity in construction, cheapness of manu- 25 facture, durability and efficiency.

With the above objects in view, and others which will appear as the nature of the invention is more fully understood, the improvement resides in the construction and 30 combination of parts set forth within the following description and falling within the scope of the appended claim.

In the drawing: Figure 1 is a perspective view of a tie constructed in accordance with 35 the present invention; Fig. 2 is a central longitudinal sectional view through one end and through one of the rail seats therefor, a rail being secured thereto; Fig. 3 is a transverse sectional view approximately on the line 3—3 in Fig. 2; and Fig. 4 is a greatly enlarged sectional view of the rail seat.

Referring now to the drawings in detail, the numeral 1 designates a tie constructed in accordance with my invention. This tie 45 preferably comprises a plastic body 2 having centrally embedded therein and coextensive therewith a metallic reinforcement in the nature of an eye beam 3. Arranged in the plastic body 1 adjacent the ends 50 thereof and resting upon the upper flange of the eye beam 3 is a metal plate 4 which is of a width almost equal to that of the tie proper, and the said plate preferably has its

outer face flush with the upper face of the said tie. This plate is centrally provided 55 with a substantially rectangular opening 5, the said opening forming a pocket for the reception of the rail receiving cushion member 6.

The cushion member 6 comprises two box 60 like structures, the lower being indicated by the numeral 7 and the upper by the numeral 8. The inner edges of the member 7, at the mouth thereof, are beveled or inclined outwardly as indicated by the numeral 9. The 65 sides or flanges 10 of the member 8 may, and preferably have, their lower edges beveled and inclined inwardly, as at 11. Packed in the members 7 and 8 is some suitable mineral substance, such as mica, indicated by the 70 numeral 12. This mineral substance 12 is crumbled or laminated to produce a plastic filler so that the upper section 8 will yield or telescope over the lower section 7 when the weight of the rolling stock is imparted 75 to the rail secured upon the cushion 6, in a manner which will now be described. The metallic plate 4, to the opposite sides of the lateral walls provided by the opening 5, is formed with orifices 13, one of which, that 80 nearest the said transverse walls of the opening 5, being threaded.

The numerals 14 designate the rail securing members. These members include flat body portions 15 having one of their ends 85 disposed angularly to engage with the base flanges as well as with the webs of the rail 16 and being provided each with an opening 17 which is adapted to register with the inner openings 13 as well as having the de- 90 pending finger 18 which is adapted to be received within the outer openings 13 in the plate 4.

The numerals 19 designate securing elements in the nature of screws which pass 95 through the openings 17 in each of the members 14 and enter the threaded orifices 13.

From the above description, taken in connection with the drawings, it will be noted that I have provided a tie in which the employment of wood or similar perishable material is entirely dispensed with; that the construction is simple, durable and effective, and that the construction and arrangement of parts will be apparent to those skilled in 100 the art without further detail explanation.

Having thus described my invention, I claim:

A plastic tie having a centrally arranged metal reinforcement, metal plates supported by the reinforcements arranged upon the tie adjacent the ends thereof, said plates having central openings, rail receiving cushion members arranged within the openings, each of said cushion members comprising two metallic elements, a mineral elastic filler be-

tween the elements, and means for securing a rail upon the tie and sustaining the same upon the cushion.

In testimony whereof I affix my signature in presence of two witnesses.

WILLIAM CROSSER.
